Inventor

United States Patent Office.

ADAM REICHERT, OF COGAN STATION, PENNSYLVANIA.

Letters Patent No. 78,009, dated May 19, 1868.

IMPROVEMENT IN SPRING-WAGON SEAT.

The Schedule referred to in these Letters Patent and making part of the same.

TO ALL WHOM IT MAY CONCERN:

Be it known that I, ADAM REICHERT, of Cogan Station, in the county of Lycoming, and State of Pennsylvania, have invented a new and improved Spring-Wagon Seat; and I do hereby declare that the following is a full and exact description thereof, reference being had to the accompanying drawings, and to the letters and figures of reference marked thereon, making a part of this specification, in which—

Figure No. 1 is a perspective view,

Figure No. 2 a longitudinal elevation, and

Figure No. 3 is a longitudinal elevation, with one end of the seat raised by means of the slides E E, represented in Figure No. 4.

The seat A is constructed as for an ordinary wagon-seat, and is connected with supports B B by means of hinges G G and spiral metallic springs C C. Under each of the supports B B are fastened, at the front and rear, the slides E E, which turn upon a pivoted at the outside ends, and can be used to elevate either end of the seat, so as to keep the same level when persons of unequal weight are riding thereon. Letter D represents the wagon-bed or box.

What I claim by my invention, and desire to secure by Letters Patent, is—

The combination of the ordinary wagon-seat A, of the springs C, constructed of iron, steel, brass, or other material, of the supports B fastened to said seat by hinges, and of the slides E E, for the purpose of elevating either end of the seat.

ADAM REICHERT.
